CAN OPENER AND THE LIKE

Filed Feb. 29, 1924

INVENTOR
Arnold J. Tanner.

UNITED STATES PATENT OFFICE.

ARNOLD J. TANNER, OF NORTH HAVEN, CONNECTICUT.

CAN OPENER AND THE LIKE.

Application filed February 29, 1924. Serial No. 695,936.

To all whom it may concern:

Be it known that ARNOLD J. TANNER, a citizen of the United States, and resident of North Haven, in the county of New Haven and State of Connecticut, has invented certain new and useful Improvements in Can Openers and the like, of which the following is a specification.

The present invention relates to tools employed for opening cans and other containers and one object of this invention is to improve the invention which forms the subject matter of application for U. S. Patent, Serial No. 616,711, filed February 3rd 1923.

Heretofore, many other types of can-openers have been designed with the object of supplying the requirement for a perfect can-opener, but generally the previously proposed can-openers are found to be so complicated, both as regards the structure and the operation, that the ordinary operator frequently does not operate the tool in the correct manner, consequently can-openers of this kind cannot always satisfactorily fill the requirement.

The conventional way of opening an ordinary food containing can is to hold the tool in an upright or semi-upright position to cut out the top end of the can, and it may be noted, can-openers which do not work in the conventional way are the ones which usually are not successfully operated.

The common type of can-opener, which operates in the conventional way, has a handle and a head, and at the end of the head, a guiding forked fulcrum is provided. The blade member is secured at the side of the head by rivets and located so that the point of the blade lies adjacent to and within the forked end of the head. It has been ascertained by experience that with this construction, the blade or cutting edge thereof is not maintained in the proper relative position with respect to the fulcrum at all times during the cutting operation, consequently, when opening a can, at certain times the tool is apt to simply tear open the top of the can, leaving a very ragged edge, which is dangerous to the operator. Furthermore, the cutting edge is not kept close to the rim of the can, the natural result being that a flange is left around the rim which renders it difficult frequently to remove the contents of the can.

According to the present invention, the tool has been carefully designed to obviate

all the disadvantages above referred to and further besides materially improving the construction and efficiency of the tool, a new method of manufacturing the same is employed, and this method greatly fosters the production of a high grade tool at a comparatively low cost.

The improved can-opener and new manner of manufacturing the same will be described hereinafter with reference to the accompanying drawings and the novel features of the invention will be defined in the appended claims. In said drawings—

Figure 1 is a side elevation of the improved can-opener;

Figure 2 is a longitudinal sectional view, with part of the handle broken away; and

Figure 3 is a detail view showing a forging or casting from which the head of the can-opener is formed.

Referring to the drawings, the improved can-opener has the handle 1 composed preferably of wood and of the shape as shown so that it will conveniently fit the hand of the operator in a position so that the hand, holding the tool, is kept well away from the head member and accordingly away from the cut edge of the can, thus to some extent eliminating danger of cutting the hand. The ferrule 2, preferably tapered, fits the reduced end of the handle. To get the best result, this ferrule should be composed of steel and substantially cup shaped with the hole 3 to receive the tang 4 of the operative member 5. The operative member has the shoulders 6 which abut against the ferrule, and these shoulders form one part of the retentive means for securing the operative member. This operative member comprises as integral parts, the aforesaid tang 4, cutting blade 7 and if desired the hook 8; and between said hook and blade a notch 9 is provided to form another part of the interlocking means for securing said operative member.

The body member 10 is formed of a malleable iron casting or drop forging and in the original shape, this body member 10 comprises the head 11 and the tang 12, which latter tang is bifurcated or forked and a portion of the head is also bifurcated. Both the tang and bifurcated part of the head converge so as to facilitate the casting operation and further to ensure proper drawing in the casting operation, the shoulder 13 is given a slight draft. This shoulder 13 forms

another part of the interlocking means for securing the operative member.

In assembling the parts of the tool, the split end of the head member and the tang 5 are first closed so as to form a slot to receive the operative member which is located in place so that the shoulder 13 fits in the notch 9. When said head and operative member are so assembled, they are then joined to the 10 handle by seating the tang of the blade together with the tang of the head member, within the bore 14 in the end of the handle. The assembled members are then driven home so that the head is tightly held in the 15 handle and the operative member is securely held by engagement of the notch 9 and shoulder 13. The operative member is also secured by co-operation of the tangs within the handle and the shoulders 6, which latter 20 abut tightly against the end of the ferrule 2.

It will be understood by means of this invention including the manner of manufacture, above described, the blade is securely retained in place without necessitating use 25 of rivets or other means requiring additional operations and accordingly there is considerable saving in the cost of manufacturing. Furthermore the appearance of the tool is not marred by rivets and besides this, the 0 part of the head member which is exposed may be polished before assembling.

The end of the head 11 has a tapering or flaring groove 15 on the underside and this 35 groove provides a guiding and extended fulcrum for the cutting blade 7. On the upper side of the end of the head, the elevated portion is formed and serves as a fulcrum for the hook member 8.

It is known that many types of can- 40 openers have been proposed having a bottle de-capping hook and frequently this hook member has no functional co-operation with the cutting member. In the present case however, it is necessary to leave sufficient 45 stock of metal above the upper surface of the head member to form the upper shoulder 6 and to get sufficient stock to render the notch 9 operative. A projecting member is thus formed and this projection can be conveniently made to operate as a de-capping 50 hook and thereby perform a double function.

It will be gathered from the above 55 description that the construction of this improved can-opener is very simple, and the operation thereof is equally simple, for it is only necessary for the operator to insert the point 17 of the blade 7 into the top 60 of the can close to the rim and then work the tool in the ordinary manner. The rim of the can is received within the grooved fulcrum which is preferably V-shaped, in cross section, as shown. The point of the blade is desirably sharpened at the back so 65 as to make penetration easy and the beveled

cutting edge 18 of the blade is on the opposite side of the blade, as shown in dotted lines. This has been found in practice to be the preferable way of sharpening the blade 70 because when sharpened this way, the blade has a tendency to roll the cut edge of the can back close to the rim of the can.

Various modifications may be made in the means for carrying out this invention, without departing from the spirit thereof and it 75 is therefore to be understood that any modification coming fairly within the terms of the appended claims shall be covered thereby.

I claim—

1. A tool, of the class described, having a handle member; a bifurcated body member adapted to be closed to form a receiving slot, an operative member adapted to be secured within said slot, said members having interlocking retentive means co-operating to secure said operative member when said members are assembled and a groove at the free end of said head adapted to operate as a 85 guiding fulcrum for the tool. 90

2. A tool, of the class described, having a handle; a head member provided with a tang; an operative member secured in said head member; said head member and its tang being bifurcated to form when closed 95 a receiving retaining slot for said operative member, said operative member and said head member having interlocking retentive means co-operating to secure said operative member when both of said members are assembled and secured within said handle and a groove on the underside of the free end of said head providing a guiding fulcrum for the tool. 100

3. A can-opener having a body member, 105 an operative member and a handle member; said body member having a slotted tang and portion to receive said operative member; interlocking retentive engaging means for securing said operative member when said body member is secured in said handle member, and said means comprising a notch and shoulder on said operative member, a shoulder at the inner end of said slot and an abutment provided by a ferrule on said 110 handle member. 115

4. A can-opener having a body member, an operative member and a handle member; said body member having a slotted tang and portion to receive said operative member; interlocking retentive engaging means for securing said operative member when said body member is secured in said handle member; said means comprising a notch and shoulder on said operative member, a shoulder at the inner end of said slot and an abutment provided by a ferrule on said handle member, and said notch and shoulder on said operative member being located in an enlarged part of said operative member 120 125 130

which extends above and below said body member providing respectively a base for a de-capping hook and a cutting blade.

5. A can-opener having a body member, an operative member and a handle member; said body member having a slotted tang and portion to receive said operative member; interlocking retentive engaging means for securing said operative member effective when said body member is secured in said handle member, and said body member being provided with a fulcrum at its outer end on both the upper and lower sides respectively for operation of the said operative member either for de-capping or cutting containers.
10. A can-opener composed of a handle, an operative member, a head member having
15. A can-opener composed of a handle, an operative member, a head member having

a bifurcated end and bifurcated tang forming a slot in said head and tang to receive 20 said operative member, retentive means provided on said members co-operating to secure said operative member and a groove on the underside of said head member operative as a guiding fulcrum for the tool. 25

7. A can-opener composed of a handle, an operative member, a head member formed with an open bifurcated end adapted to be closed to provide a slot to receive said operative member and retentive means provided 30 on said members co-operating to secure said operative member within said slot.

Signed at New Haven, county of New Haven, State of Connecticut, this 28 day of Feb., 1924.

ARNOLD J. TANNER.
